UNITED STATES PATENT OFFICE.

LIZZIE ROYS, OF NEW YORK, N. Y., ASSIGNOR TO THE BUTTERICK PUBLISHING COMPANY, (LIMITED,) OF SAME PLACE.

DESIGN FOR A WALKING-SKIRT.

SPECIFICATION forming part of Design No. 18,344, dated May 22, 1888.

Application filed April 20, 1888. Serial No. 271,345. Term of patent 3½ years.

To all whom it may concern:

Be it known that I, LIZZIE ROYS, of the city, county, and State of New York, have invented and produced a new and original Design for a Pattern of a Lady's Walking-Skirt; and I do hereby declare that the engraved prints accompanying this specification convey to any one accustomed to using paper patterns a clear understanding of how a garment made up by the pattern will appear.

The design shows a round walking-skirt that displays a kilted lower part and exhibits its plaits turning from the center of the front; a full drapery forming a short pointed tablier on the front, falling in a long full drapery on

the right side of the back, and displaying draping plaits in its right edge near the top on the left hip and in its upper edge back of the hip, and loopings at the back, a left back drapery displaying draping plaits in its upper and front edges, and loopings.

What I claim as my invention, and desire to secure by Letters Patent, is—

The design for a lady's walking-skirt, as shown in the engraved prints accompanying this specification.

LIZZIE ROYS.
